US0D1003908S

(12) **United States Design Patent** (10) Patent No.: **US D1,003,908 S**
Martinez Galan (45) Date of Patent: ** Nov. 7, 2023

(54) **DISPLAY SCREEN OR PORTION THEREOF HAVING A GRAPHICAL USER INTERFACE**

(71) Applicant: **Stryker Corporation**, Kalamazoo, MI (US)

(72) Inventor: **Jose Daniel Martinez Galan**, Redmond, WA (US)

(73) Assignee: **Stryker Corporation**, Kalamazoo, MI (US)

(**) Term: **15 Years**

(21) Appl. No.: **29/756,795**

(22) Filed: **Oct. 30, 2020**

(51) LOC (14) Cl. **14-04**

(52) U.S. Cl.

USPC **D14/485**

(58) **Field of Classification Search**

USPC D14/485-495

CPC G06F 3/048-04897; A61B 5/322; A61N 1/37247; A61N 1/3993; G06T 2200/24; G06T 2210/41; G16H 40/67

(57) **CLAIM**

The ornamental design for a display screen or portion thereof having a graphical user interface, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof having a graphical user interface.

The dot-dashed broken lines depict a display screen or portion thereof and form no part of the claimed design. The dashed broken lines depict portions of the graphical user interface and form no part of the claimed design.

1 Claim, 1 Drawing Sheet
